SHELTER SUPPORT

Ralph B. Feffer, Jr., Phoenix, Ariz.

Application November 21, 1957, Serial No. 48,590

Term of patent 14 years

(Cl. D13—4)

FIG. 1

FIG. 2

I claim:

The ornamental design for a shelter support, as shown.
